FLUID CIRCULATING SYSTEM

William H. Kuster, San Francisco, and Edwin A. Glynn, Lodi, Calif.

Application August 7, 1942, Serial No. 454,059

3 Claims. (Cl. 18—6)

This invention relates to the vulcanizing art and particularly to vulcanizing operations which are effected in a closed kettle by means of a hot gas confined under pressure in the kettle.

In order to assure a proper vulcanizing action, it is desirable to circulate the confined gas, and our principal object is to provide a gas circulating system, disposed entirely within the kettle, by means of which a very even distribution of the heated gas over the entire area of the kettle is effected, without any possibility of a "channelling" flow action being had.

The kettle and the circulating system therein are particularly designed for vulcanizing treads on tires, and another object of the invention is to arrange the circulating system so that the circulating gas, adjacent its point of greatest pressure in the kettle, impinges directly on the tread of a tire so as to have a quick vulcanizing action thereon, and thus avoiding the necessity of leaving the tires in the kettle for such a length of time as would cause the sidewalls of the tires to become unduly heated.

Another object is to provide, as a part of the circulating system, a means for supporting the tires so that the treads are disposed in the path of even gas pressures, so that a tread is subjected to the same even vulcanizing action all about its circumference.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

The figure on the drawing is a sectional elevation of a vulcanizing kettle equipped with our improved circulating system.

Referring now more particularly to the characters of reference on the drawing, the kettle comprises a pair of substantially semi-spherical heated insulated shell sections 1 and 2. The adjacent ends of these sections are open to each other and lie in a vertical plane, and while they are capable of being moved apart for insertion and removal of the tires, as shown in our co-pending application for patent, Serial No. 454,058, filed August 7, 1942, now U. S. Patent No. 2,346,973, they are locked together in pressure-tight relation when in operation. This locking is preferably effected by the device shown in our co-pending application, Serial No. 454,060, filed August 7, 1942. The sections are each provided

with an interior wall 3 spaced from the shell proper and when the sections are secured together, these walls together with the outer shell form a continuous chamber 4 about the interior of the shell. The wall 3 is disposed relative to the wall shell so that the cross sectional area of the chamber at any point between its ends is substantially constant. The wall 3 is provided with perforations 5, freely distributed throughout its extent, for the passage of gas therethrough.

The shell section 1 is provided with a horizontal axially disposed open ended tubular member 6 connected to the adjacent wall 3 at the end of the section. A fan chamber 7 is interposed between the adjacent end of the member 6 and the adjacent portion of the chamber 4, and opens freely into said member. The fan chamber has relatively restricted communication with the chamber 4 by means of an annular passage 8 flaring radially out into chamber 4.

A similar tube 9 is aligned with the tube 6 but is spaced therefrom sufficient to provide a gap 10 therebetween at adjacent ends. This tube is mounted axially in the shell section 2, but is merely closed at its outer end and does not directly communicate with the chamber 4. Both tubes are provided with freely distributed perforations 11 somewhat larger than the perforations 5. The combined area of all perforations 5 is somewhat greater than the combined area of all perforations 11 plus the gap 10, due allowance being made for pressure losses in the circulating gas, owing to friction at the perforations.

A motor driven fan 12 is mounted in the chamber 7, drawing from the tube 6 and discharging into the adjacent end of chamber 4 all about the same through the annular passage 8. The gas to be circulated is initially discharged into the kettle at any suitable point, but preferably into the tube 6 adjacent the fan chamber by means of a conduit 13 facing the fan. The diameter of the tube members 6 and 9 is no greater than the bead size of any tire, and if a tire T of a larger size is to be vulcanized it is supported from either tube, so as to be concentric therewith and with the shell, by a suitable spider or spacer as indicated at 14. In operation, assuming the kettle to be closed and filled with gas to be circulated, the fan is started, which draws the gas from the tubes and discharges the same into the chamber 4. Due to the restricted passage or throat 8 through which the gas is initially forced, the pressure is gradually built up within the

chamber. The gas in the chamber then escapes in the form of small streams through the perforations 5, all such streams initially moving substantially radial of the kettle; those in whose path the tire is disposed impinging directly upon the tread of the tire with a jet action before these various small streams become dissipated and their pressure materially lessened.

Due to the relative area of the perforations in the wall 3 and the tubes, as previously set forth, there is no tendency for the gas to move directly from one to the other and a "channeling" action, which would otherwise occur, is prevented. Instead an even distribution of the hot gases within the kettle results. The use of the gap 10 provides a relatively large gas intake opening substantially at the center of the kettle, tending to cause the gas from all points of the kettle to have a radial flow toward the center. In cases where it may be desired to concentrate a gas flow between the wall 3 and a certain portion only of the axial return conduit unit 6 and 9, we may mount one or more removable slide sleeves 15 over said conduit, so as to cover any desired number of perforations therein and thus cause the gas being drawn toward said conduit unit from substantially the entire area of the wall 3, to move toward a selected portion only of said return conduit. In this manner any tire etc. can be vulcanized more quickly than would otherwise be the case, and the use of such a sleeve would be resorted to when a single tire is being treated.

In the case of large size tires whose side walls might be damaged by long exposure to the hot gas, a cold water bag may be mounted in the tire so as to have a cooling action on the side-walls for some time without affecting the desired hot vulcanizing action on the thicker tread portion of the tire.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a de-

parture from the spirit of the invention, as defined by the appended claims.

Having thus described our invention what we claim as new and useful and desire to secure by Letters Patent is:

1. A vulcanizing kettle comprising a wall forming an internal gas chamber, a substantially spherical and freely perforated shell within and spaced from the walls of the chamber, a 10 perforated conduit in the shell open at one end, an axial fan chamber interposed between the open end of the conduit and the adjacent portion of the gas chamber and connecting the same, a fan in said fan chamber drawing from the conduit, and means forming a circumferential restricted passage leading into the gas chamber from about the periphery of the fan chamber, the walls of the passage diverging into said gas chamber the diameter of the fan chamber being relatively small compared with that of the gas chamber.
2. A vulcanizing kettle comprising a wall forming an internal gas chamber, a substantially spherical and freely perforated shell within and spaced from the walls of the chamber, a 15 perforated conduit unit in the shell communicating with the space between the walls of said chamber and said shell, and means to circulate gas confined within the kettle from the conduit and back to the conduit through the perforations in the shell and conduit; a relatively large opening being provided in the conduit unit all about the same in a zone substantially centrally of the kettle.
3. A tire vulcanizing kettle comprising a pair of complementary kettle sections of greater internal diameter than a tire and movable horizontally relative to each other to close or open the kettle, a horizontal tire support in and fixed 20 with each section disposed axially thereof and extending parallel to the direction of relative movement of the sections, said support being adapted to relatively slide through the central opening of a tire; there being means to circulate 25 a heated gas within the kettle when the sections are closed.
